CLAIM

The ornamental design for the wood grill scraper, as shown and described.

DESCRIPTION

FIG. 1 is a left side view of the design for a first embodiment of a wood grill scraper;

FIG. 2 is a top view thereof;

FIG. 3 is a front view thereof;

FIG. 4 is a bottom view thereof;

FIG. 5 is a right side view thereof;

FIG. 6 is a back view thereof;

FIG. 7 is a front, bottom perspective view thereof;

FIG. 8 is a left side view showing a second embodiment for a wood grill scraper;

FIG. 9 is a top view thereof;

FIG. 10 is a front view thereof;

FIG. 11 is a bottom view thereof;

FIG. 12 is a right side view thereof;

FIG. 13 is a back view thereof; and,

FIG. 14 is a front, bottom perspective view thereof.

The broken lines in the drawings depict portions of the wood grill scraper that form no part of the claimed design.
